UNITED STATES PATENT OFFICE.

THOMAS McLOYD COMEGYS, OF SHREVEPORT, LOUISIANA.

ORTHODONTIC APPLIANCE.

Application filed September 8, 1923. Serial No. 661,601.

To all whom it may concern:

Be it known that I, THOMAS McLOYD COMEGYS, a citizen of the United States, and a resident of Shreveport, in the parish of 5 Caddo and State of Louisiana, have invented a new and Improved Orthodontic Appliance, of which the following is a full, clear, and exact description.

This invention relates to an orthodontic 10 appliance, and has for an object the provision of a simple and efficient appliance which can be readily disposed in the mouth for the purpose of maintaining the teeth in proper alignment with respect to their normal curvature or contour.

Another object concerns the provision of a simple and efficient device which can be very easily adjusted to maintain and give pressure along a definite curve on the teeth 20 so as to maintain the teeth in their proper position.

The invention is illustrated in the drawings, of which—

Figure 1 is a plan view of the device applied to a set of teeth and exerting pressure on the outside of the teeth to hold 25 them in proper alignment;

Fig. 2 is a perspective view of the device shown in Fig. 1;

Fig. 3 is a plan view of a set of teeth showing a similar device applying pressure to the inner surface of the teeth to hold 30 them in proper alignment; and

Fig. 4 is a perspective view of the device shown in Fig. 3.

The form of the invention shown in the drawings is a preferred form, although it is understood that modifications in the construction and arrangement of the parts and 40 in the character of the materials used may be adopted without departing from the spirit of the invention.

The form of the invention shown in the drawings comprises a pair of anchor bands 45 1 and 2 which are adapted to be disposed around teeth on opposite sides of the mouth, these bands being preferably connected thereto by any suitable means, such as by cement.

Between these bands there extend two teeth engaging elements, such as 3 and 4, which may be in the form of flexible bars or rods connected at one end to the anchor bands 1 and 2 and slidably engageable with

each other along their other ends. These 53 bands are curved or bow-shaped, so that they can lie along either the inner or the outer surface of the teeth, lying intermediate the teeth to which the anchor bands are fastened, and by being adjustable the 60 pressure which these slideable elements or bars can exert on the teeth can be determined so as to keep teeth which might otherwise tend to get out of line, in proper alignment with the others. As shown, the 65 slideable and adjustable end portions of the elements 3 and 4 are engageable by reason of the provision on each of tubular members or sleeves such as 5 through which portions of the elements extend. The fit of 70 these sleeves on the bars or rods is sufficiently tight so that they will retain their adjusted position.

As shown in Fig. 1, the anchor bands are connected to two inner teeth such as 6 and 75 7, and the elements 3 and 4 are curved to extend outside the teeth intermediate the teeth 6 and 7 to hold them in position and prevent their spreading outward; whereas in Fig. 3 the same sort of device is shown 80 applied in such position as to exert pressure outwardly against the inner surface of the intervening teeth. In this way the deformation of teeth, especially the front teeth, from their normal line of contour is 85 prevented.

In Figs. 3 and 4, the anchor bands are designated by the numerals 8 and 9; the slideable elements, by 10 and 11; and the engaging means, by the numeral 12. 90

What I claim is:—

An orthodontic device which includes a pair of anchor bands adapted to be cemented to teeth in the mouth, a pair of teeth-engaging elements connected at one end to the 95 anchor bands, sleeves on the other ends of said elements, each sleeve adapted to receive portions of the other element than the one on which it is mounted whereby the elements may be adjusted to bear 100 against the surface of the teeth intervening between the anchor bands to hold them in their normal alignment, the sleeves adapted to engage with the elements which they embrace with sufficient friction to hold 105 the elements in any adjusted position.

THOMAS McLOYD COMEGYS.
